UNITED STATES PATENT OFFICE.

RUDD HARDESTY, OF DENVER, COLORADO.

SECTIONAL CULVERT.

1,044,044.

Specification of Letters Patent. Patented Nov. 12, 1912.

Application filed September 27, 1911. Serial No. 651,823.

To all whom it may concern:

Be it known that I, RUDD HARDESTY, a citizen of the United States of America, residing at Denver, in the county of Denver and State of Colorado, have invented certain new and useful Improvements in Sectional Culverts, of which the following is a specification.

My invention relates to new and useful improvements in sectional culverts and its object resides in the provision of a culvert of this character, the sections of which are each composed of two semicircular sections which are formed with integral means whereby they may be readily and firmly connected without the use of rivets, bolts or other separate fastening devices. Culverts thus constructed are strong, durable and inexpensive and the sections of which they are composed are nestable to facilitate transportation and handling.

An embodiment of my invention is illustrated in the accompanying drawings in the various views of which like parts are similarly designated and in which,

Figure 1 represents a side elevation of a section of the improved culvert. Fig. 2 a perspective view of one of the semi-circular halves of which said sections are composed. Fig. 3, a transverse section along the line 3—3, Fig. 1, drawn to an enlarged scale, and Fig. 4, a similar section taken along the line 4—4, Fig. 1.

Referring to the drawings by numerical reference characters the numeral 2 designates the semi-circular sections of which each culvert section is composed and which are made of sheet-metal preferably formed with transverse corrugations (not shown) for the purpose of strengthening the structure.

Each of the two halves of the culvert sections is provided along its longitudinal edges with offset lips 3 which provide seats to receive the corresponding edges of the other half when the parts are assembled in the construction of the culvert.

The lips 3 are formed integrally of the metal of which the semi-circular sections are composed, by providing the latter at their longitudinal edges with pairs of transverse, preferably parallel slits 4, and then offsetting the portions between them either inwardly or outwardly, all of which is readily accomplished in one operation by means of an ordinary stamping press.

The lips of the two complementary halves of each culvert-section are respectively set inwardly and outwardly so that when the said halves are assembled to form the culvert, the lips on the one will be exposed upon the circumferential surface thereof while those on the other extend along the interior surface of the same, as is clearly shown in the drawings.

The lips of the two halves of the culvert sections extend substantially parallel to the intermediate portions of the sections at a distance from said portions slightly exceeding the thickness of the material of which the sections are made so that the lips on each half will lie flat against the surface of the other half. The joint between the sections of each culvert-section will thereby be tightly closed and the said sections may be instantly placed in their relative positions without fitting and without the use of tools. The lips 3 of each half of the culvert sections are out of line with those on the other half of the same section so as not to interfere with each other when the two halves are assembled.

Having thus described my invention what I claim and desire to secure by Letters-Patent is:

1. A culvert composed of two semi-circular sections each having seats for the longitudinal edges of the other, the said seats being formed by inwardly offset lips on one section and outwardly offset lips on the other section, which lips extend substantially parallel to the intermediate portions of the sections at a distance from said portions slightly exceeding the thickness of the material of which said sections are made.

2. A semi-circular culvert-section having along its longitudinal edges, seats formed by offsetting portions of the material of which said section is composed, between transverse slits, said portions extending substantially parallel to the intermediate parts of the sections, at a distance from said parts slightly exceeding the thickness of the material of which said sections are made.

3. A culvert composed of semi-circular sections one of which has seats for the longitudinal edges of the other, said seats being formed by offset lips integral with the material of which said section is composed, and extending substantially parallel to the intermediate portions of the sections, at a distance from said portions slightly exceed-

ing the thickness of the material of which said sections are made.

4. A culvert composed of two semi-circular sections, each having seats for the longitudinal edges of the other, the said seats being formed by inwardly offset lips on one section and outwardly offset lips on the other section, and said lips being formed integral with the material of which said sections are composed, and extending sub-

stantially parallel to the intermediate portions of the sections, at a distance from said portions slightly exceeding the thickness of the material of which said sections are made.

In testimony whereof I have affixed my 15
signature in presence of two witnesses.

RUDD HARDESTY.
